(57) **CLAIM**
The ornamental design for a lighting device, as shown and described.

DESCRIPTION

FIG. 1 is a top, front and left side perspective view of a lighting device showing my new design;
FIG. 2 is a left side elevational view thereof, the right side elevational view being a mirror image;
FIG. 3 is a front elevational view thereof;
FIG. 4 is a rear elevational view thereof;
FIG. 5 is a top plan view thereof; and,
FIG. 6 is a bottom plan view thereof.
The broken-line disclosure represents portions of the article in which the claimed design is embodied, but which form no part of the claimed design.
